DRAPEY SUPPORTING DEVICE AND MEANS FOR APPLYING THE SAME

Fred R. Williams and Alvin C. Williford, Houston, Tex.

Application September 21, 1953, Serial No. 381,330

1 Claim. (Cl. 160—348)

This invention relates to a drapery supporting device and means for applying the same, and more particularly to an improved drapery hook and apparatus for attaching the same to the fabric of the drapery.

In the making of draperies, as heretofore customarily practiced, the fabric is formed with vertically extending folds or pleats at the top, and hooks are sewed to the fabric at spaced intervals, usually at the seams where the pleats are sewed, by which the drapery may be suspended from a suitable support. The attachment of the hooks in this manner is a tedious and time consuming operation, since each hook must be individually sewed in place, and the labor thus involved constitutes a very substantial item in the cost of the article.

Numerous attempts have been made to overcome the above difficulty, by the use of hooks formed with pins, bends or other means for quickly attaching them to the fabric, but such devices have proven unsatisfactory in use, particularly in connection with relatively heavy draperies, due to the inadequate support afforded which often causes stretching or tearing of the fabric.

It is an important object of the present invention to overcome the above disadvantages and to provide a drapery supporting device which is attached to the fabric without the necessity of sewing the same thereto.

Another object of the invention is the provision of drapery supporting means which is secured to the fabric of the drapery by the use of fastening means which does not penetrate the fabric.

A further object of the invention is to provide drapery supporting means which may be easily secured to the fabric of the drapery at any selected one of a number of positions at differently spaced locations relative to the upper extremity of the fabric, and which is readily removable therefrom without injury to the fabric.

A further object of the invention is the provision of a drapery supporting device embodying a hook member having a shank portion provided with an opening which is of key-hole shape, and a backing plate formed with a number of longitudinally spaced openings therein, whereby the hook member may be secured to the plate by a rivet, eyelet, or the like, in a manner to be readily removed therefrom by movement of the shank of the hook member relative to the plate to permit disengagement of the shank from the eyelet through the key-hole opening.

Another object of the invention is the provision of drapery supporting means of the type referred to which includes a hook member and a backing plate, and which is secured to the fabric by a fastening element adapted to be inserted between folds of the fabric, which have been sewed together, and through registering holes in the member and plate.

A further object of the invention is to provide apparatus for applying drapery supporting means of the kind described to drapery fabric, and which embodies means for locating the backing plate and hook member in the desired relative positions on the fabric, and with the opening in the hook member in registration with a selected

2

one of the openings in the backing plate, and for inserting a fastening element through the registerig openings to secure the hook member to the plate and fabric.

The foregoing and other important objects and advantages of the invention will be apparent from the following detail description, constituting a specification of the same, when considered in conjunction with the annexed drawings, wherein—

Figure 1 is a side-elevational view showing the apparatus for applying the drapery supporting device of the invention to drapery fabric, and showing the apparatus in its initial position;

Figure 2 is a side-elevational view similar to that of Figure 1, showing the apparatus of the invention in another position of its operation in the securing of the drapery supporting device to the fabric;

Figure 3 is a cross-sectional view, taken along the line 3—3, on an enlarged scale, looking in the direction indicated by the arrows;

Figure 4 is a fragmentary perspective view, partly in cross-section, and on an enlarged scale, showing the arrangement of the parts of the positioning means by which the drapery supporting device and fabric are positioned preliminary to the operation of the apparatus to secure the same to the fabric;

Figure 5 is a front elevational view, partly in cross-section, and on an enlarged scale, showing the backing plate and fabric in position on the apparatus, with the fastening element in position to secure the hook member to the fabric and preliminary to the placing of the hook member in position prior to the securing operation;

Figure 6 is a cross-sectional view, taken along the line 6—6 of Figure 5, looking in the direction indicated by the arrows, and showing the hook member placed in position to be secured to the fabric by operation of the apparatus;

Figure 7 is a cross-sectional view similar to that of Figure 5, showing the parts of the apparatus in the position which they occupy at the completion of the securing operation;

Figure 8 is a fragmentary perspective view of a portion of the drapery showing the drapery supporting device secured thereto;

Figure 9 is a perspective view on a somewhat enlarged scale, showing the details of construction of the backing plate of the drapery supporting device;

Figure 10 is a perspective view similar to that of Figure 9, illustrating a somewhat modified form of fastening element by which the hook member is secured to the backing plate; and

Figure 11 is a perspective view of the fastening element illustrated in Figure 10, showing the same detached from the backing plate and hook member.

Referring now to the drawings in greater detail, the invention is illustrated in connection with the manufacture of articles of drapery, such as curtains, or the like, but it will be understood that the supporting means and the apparatus by which the same is secured to the fabric are capable of more general application, and may be employed wherever means of a similar character are to be applied to articles of the same general character. In the present illustration the numeral 10 designates a piece of fabric, such as drapery material, which may consist of one or more layers of fabric, as indicated at 10 and 12 in Figure 8, which layers may be formed with or without hem portions, as indicated at 16 and 18, respectively, at their upper marginal portions. The layer of fabric 12 may be of decorative material, forming the front of the drapery, while the layer 14 may take the form of a lining forming the rear face of the drapery.

In order to form decorative pleats on the drapery, and to provide means for supporting the same from suitable

supports, such as curtain rods, or the like, the layers of fabric may be formed into folds 20 and 22, by stitching as indicated at 23, at spaced intervals along its upper margin, such folds forming edges positioned in opposed parallel relation, as clearly seen in Figure 8. In forming the folds 20 and 22 the fabric may be stitched together, as seen at 23, if desired, to retain the edges of the folds permanently in parallel opposed relation. The formation of the folds 20 and 22 will provide a continuous portion 26, of the fabric, extending forwardly of the front surface of the drapery which connects the folds and which is adapted to be folded into pleats 28, to provide an ornamental or decorative effect.

Suitable supporting elements, which in the present illustration take the form of hooks 36, are attached to the drapery in the locations where the edges of the folds 20 and 22 are positioned, in the manner indicated in Figure 8, and these support elements are secured to the fabric by means of eyelets 34, or other similar fastening elements, which pass through registering openings in the hook and in a backing plate, such as that illustrated at 38, positioned inside of the portion 26, and on the opposite face of the fabric to that on which the hook element is located.

The hook elements 36 are preferably formed as illustrated in Figures 6 and 8, and are provided with widened shank portions 40, having an opening 42 therethrough, which is of key-hole formation, the narrow portion of the opening being of a size corresponding substantially to the external diameter of the fastening element, such as the eyelet or rivet 34, and the wide portion of the opening 42 being of a size to permit free passage therethrough of the head of the eyelet.

As best seen in Figure 9 of the drawings the backing plate 38 is somewhat elongated and may be formed with rearwardly extending longitudinal side portions 44, 44, to form a channel, and the plate preferably has a number of openings 46, at equally spaced intervals longitudinally thereof.

Suitable openings 48 are also provided at each of the ends of the backing plate, by which the same may be sewed to the fabric when desirable or expedient. As will be seen from an examination of Figures 6, 9 and 10 of the drawings, the openings 46 are equally spaced longitudinally of the backing plate, but the end ones of the openings 46 are spaced at somewhat different distances from the respective ends of the plate. By such arrangement of the openings in the backing plate the hook element may be attached to the drapery at different distances from the upper edge thereof, while at the same time the backing plate may always occupy the same position relative thereto, and by reversing the backing plate the distances of the holes 46 from the upper edge of the drapery will be somewhat changed, so that a great number of points of attachment at varying distances from the upper edge of the drapery is provided for the hook element.

It will be apparent that in the use of the above described supporting means the fastening element or eyelet 34 may be inserted through the opening 42 of the hook element and extended between the folds 20 and 22 of the fabric, without penetrating or otherwise damaging the fabric, and may also be inserted through one of the openings 46 of the backing plate, whereupon the fastening element may be clamped or set to clampingly engage the hook member and backing plate to the fabric to securely hold the hook in place thereon at the desired location.

In the event that it should be desired to remove the hook from the fabric the hook member may be forced downwardly on the shank of the fastening element 34, until the head of the element is positioned opposite the wide portion of the key-hole opening 42, whereupon the hook element may be detached from the fastening element. The backing plate may then be removed, by push-

ing the head of the eyelet through the opening in the sewed seam.

The apparatus by which the supporting device is applied to the drapery is illustrated in detail in Figures 1 through 7 of the drawings, and includes an operating head 50, which is adapted to be attached in any convenient manner to a suitable support, such as a table or bench indicated at S, and which carries die and drive tool mechanism 52 and 54, respectively. The drive tool mechanism, as best illustrated in Figure 3, comprises a plunger 56, which moves vertically in a cylindrical chamber 58 in the head, and is urged upwardly therein by a coil spring 60, which bears at its upper end on a downwardly facing external shoulder 62 on the plunger, and at its lower end on an internal upwardly facing shoulder 64 carried by the head. The plunger has a longitudinal external groove 66 therein, into which a pin 68 carried by the head extends, to limit upward movement of the plunger in the chamber by engagement with the plunger at the lower end of the groove.

The lower end of the plunger 56 is of reduced diameter and extends downwardly from the chamber 58, and carries at its lower end a stem 70, to the lower end of which a cylinder 72 is attached, and within the cylinder 72 there is a plunger 74, having a stem 76 which extends through the bottom of the cylinder. The plunger 74 is yieldingly urged downwardly in the cylinder 72 by a coil spring 78, which bears at its upper end against the lower end of the stem 70, and at its lower end against the top of the plunger. The lower end of the cylinder 72 forms the drive tool and the stem 76 is adapted to hold the tubular eyelet 34 therein in position to be set by operation of the apparatus to secure the hook member to the backing plate and fabric.

The plunger 56 is adapted to be moved downwardly in the chamber 58 by a lever 80, which bears at one end against the upper end of the plunger, and is pivotally connected at its other end to a link 82. The lever 80 is pivotally mounted mediate its ends by suitable means, indicated at 84, on the head 50. The link 82 is pivotally connected by suitable means, such as a pin 86, to one end of a second link 88, whose other end is pivotally attached to the head 50, and the pin 86 extends through an elongated opening 90 in one end of an operating lever 92, which is pivotally secured mediate its ends to the head, and extends downwardly beneath the same. The lower end of the lever 92 carries a foot pedal 94, by which the same may be operated. Upon operation of the lever 92 by depressing the pedal 94, the lever will be moved to the position illustrated in Figure 2, wherein the pin 86 is moved toward the head 50, to cause the lever 80 to be moved in a direction to press the plunger 56 downwardly in the chamber 58, thus moving the drive tool 72 downwardly toward the die 98 of the apparatus. Upon release of the lever 92 the parts will be returned to the position of Figure 1, by the spring 60 which moves the plunger 56 to its fully retracted position in the chamber 58.

The die mechanism of the apparatus comprises a die member 98, which is carried on a support 100 extending forwardly from the head 50 beneath the drive tool mechanism, and which has an upwardly opening widened groove 102 in its upper face, forming a trackway for a movable stop element 104. The stop member 104 is adjustable longitudinally of the support 100 in the groove 102, and is carried on a shaft 106, which is slideable in the head 50, and is held in any desired position of adjustment therein by means of a set screw 108, or otherwise, whereby the position of the stop member 104 relative to the drive tool and die may be adjusted as desired. The stop member 104 is provided with a step portion 110, whose forward edge is engageable with an end of a backing plate 38 in position in the groove 102, to locate the backing plate at a desired position relative to the drive tool and die, and the stop member also has a

back wall portion 112, which is engageable with the upper edge of the drapery so that the same will be positioned at a predetermined location relative to the backing plate during the operation of the apparatus.

The head 50 also carries forwardly extending shafts 114, 114, which are located on opposite sides of the support 100 in substantially parallel relation thereto, and upon which the fabric may rest in the manner shown in Figures 5, 6, and 7, so that the folds 20 and 22 may be positioned on top of the backing plate in position for the insertion of the fastening element 34 therebetween in the operation of securing the hook member and backing plate to the fabric.

In making the drapery the fabric is formed with the end portions 16 and 18 along the upper edge of the drapery and the fabric is then folded and stitched as indicated at 23 to form the folds 20 and 22 providing the portion 26. When the fabric has thus been formed with the required number of folds a backing plate 38 is placed in the groove 102 of the support 100 with its side portions 44 directed upwardly, as seen in Figures 5, and 7, and one end of the backing plate abutting the forward edge of the step portion 110 of the stop member 104, whereby a selected one of the openings 46 of the backing plate will be positioned above the die 98, and directly beneath the drive tool 72. The drapery is then positioned on the support with the seam 23 positioned above the backing plate, so that the meeting edges of the folds 20 and 22 pass over the opening 46, as best seen in Figures 5 and 7, and the upper edge of the drapery is engaged with the upright wall 112 of the stop member 104. With the drapery and backing plate thus positioned on the support a fastening element, such as a tubular eyelet or rivet 34, is positioned on the stem 76 to engage the lower end of the drive tool 72 and a hook member 36 is placed over the eyelet with the shank of the eyelet extending through the narrow portion of the key-hole opening 42, as shown in Figure 6.

In position of the parts it will be seen that the narrow portion of the key-hole opening 42 is in registration with the selected one of the openings 46 of the backing plate, and upon depressing the lever 92 by means of the foot pedal 94, the plunger 56 may be forced downwardly in the head to move the drive tool 72 downwardly, thus forcing the lower end of the eyelet 34 between the folds 20 and 22 of the drapery and through the selected one of the holes 46 in the backing plate into engagement with the die 98, whereby the lower end of the eyelet will be spread or set in the manner indicated in Figure 7, to securely clamp the folds of the fabric between the hook member and the backing plate, and attach the hook securely to the drapery at the desired location. Upon releasing the lever 92 the plunger 56 is returned to its uppermost position by the spring 60, whereby the drive tool 72 will be moved upwardly, whereupon the drapery with the hook attached thereto may be removed from the apparatus and the operation repeated until the required number of hooks has been attached along the upper marginal portion of the drapery.

In the event that it should be desirable to attach supporting hooks to the end portions of the drapery, where there are no pleats, this may be accomplished with the

fastening means illustrated in Figures 10 and 11, wherein a staple-like element 116 is illustrated, which may have a flattened central portion 113, and pointed opposite end portions 120, 120. In applying a hook to the fabric by the use of this staple device a backing plate is positioned between the layers of fabric, and a hook member 36 is positioned on the outer surface of the fabric layer 14 with the hook member located between two of the openings 46 of the backing plate, and the pointed end portions 120 of the fastener element 116 are passed through the openings of the backing plate, penetrating the fabric and also passing through the key-hole opening 42 of the hook member, whereupon the pointed end of the fastener may be bent outwardly, as seen in Figure 10, to securely fasten the hook member to the plate.

It will thus be seen that the invention, as described above, provides a drapery supporting device of simple design and economical manufacture, and apparatus for applying the same, whereby such devices may be quickly and securely attached to the drapery without the necessity of sewing the same thereto.

The invention has been disclosed herein in connection with certain specific embodiments of the same, but it will be understood that this is intended by way of illustration only, and that numerous changes can be made in the construction and arrangement of the various parts without departing from the spirit of the invention or the scope of the appended claim.

Having thus clearly shown and described the invention, what is claimed as new and desired to secure by Letter of Patent is:

A supporting device for an article of drapery having folds whose edges are arranged in opposed parallel relation comprising a hook and an elongated backing plate member disposed on opposite sides of the folds and overlying said edges, said hook member having a flat shank portion provided with a key hole shaped opening therethrough and said plate member having substantially equally longitudinally spaced openings therethrough the endmost openings of said plate member being spaced at different distances from the respective ends of the plate member, said plate member also having a channel shaped portion mediate its ends whose free side edges are spaced apart a distance to receive between them said shank portion in engagement with the folds, a selected one of the openings of said plate member being disposed in registration with the narrow portion of said key hole shaped opening, and fastening means extending through the registering openings and between the edges of the folds and engageable with the members to clampingly secure the members to the folds.
